UNITED STATES PATENT OFFICE

2,568,788

WATER PUMP CAP-SCREW REMOVER

Peter H. Bossen, Watertown, S. Dak.

Application May 21, 1948, Serial No. 28,341

1 Claim. (Cl. 81—114)

1

This invention relates to a water pump cap-screw remover, especially adapted for removing cap-screws from a water pump of Ford V-8 and Mercury engines, where the cap-screw is located between the radiator connecting hose and the water pump proper.

A further object of this invention is the production of a simple and efficient means for firmly gripping a water pump cap-screw to facilitate the removal of a water outlet cap-screw which may have become corroded and is otherwise difficult to remove by ordinary methods.

Other objects and advantages of the present invention will appear throughout the following specification and claim.

In the drawing:

Figure 1 is a side elevational view of a portion of an engine and engine block, associated with a portion of a radiator, and showing the cap-screw remover and adjoining parts in longitudinal section;

Figure 2 is a side elevational view of the cap-screw remover;

Figure 3 is an end elevational view of the device with the adjusting plug removed;

Figure 4 is an end elevational view of the device;

Figure 5 is a side elevational view of the adjusting plug;

Figure 6 is a perspective view of the spring collet;

Figure 7 is an end elevational view looking at the inner end of the spring collet.

By referring to the drawing, it will be seen that 10 designates a fragmentary portion of an engine which supports a water pump 11 at one end having a projecting right-angularly extending water pump outlet 12 at its lower end. This outlet 12 is in line with the outlet 13 of the radiator 14, the outlet 13 being spaced from the outlet 12. These outlets 12 and 13 are adapted to be connected by the conventional removable hose not shown. The conventional water pump outlet cap-screw 15 secures the pump at its lower end to the engine 10, as shown in Figure 1, and the head 16 of the cap-screw 15 is located at the inner end of the water pump outlet 12. Because of this location of the cap-screw 15, the head 16 thereof becomes corroded by the water which passes through the outlet 12, which outlet forms a communication with the radiator outlet 12 through the medium of a connecting hose. The location of the cap-screw 15 makes its removal, by ordinary methods, very difficult. Consequently, I have devised a device in the nature of a

2

specially designed cap-screw remover to overcome this difficulty.

This cap-screw remover comprises a hollow cylindrical or tubular body 17 having a tapered inner extremity 18 preferably tapered at approximately 60°. An integral external hexagonal nut portion 19 is carried by the outer or opposite end of the body 17. The outer end of the body 17 is provided with an internal threaded portion 20. The body 17 also is provided with an inner cylindrical smooth bore 21 having an inwardly tapering portion 22 at its inner extremity adjacent the head 16 of the cap-screw 15.

A spring collet 23 is slidably mounted in the bore 21 and comprises a plurality of spring jaws 24 defined by the longitudinal slots 25 which are formed in the spring collet 23 and extend through the inner end of the collet 23 but terminate short of the opposite end of the collet. The jaws 24 taper inwardly or are beveled at 26, at their inner extremities, so as to cause the jaws 24 to be forced radially inwardly in gripping action against the head 16 of the cap-screw as the inner ends 26 contact the inwardly tapering portion or beveled inner face 22 of the body 17 while the collet 23 is being forced toward said cap-screw. The inner faces of the jaws 24 are preferably beveled, as at 27, at their inner extremities to facilitate the passing of the ends of the jaws 24 over the head of the cap-screw 15 to a gripping position, and to define a plurality of chisel-like cap-screw gripping elements. The collet 23 is cylindrical exteriorly, and hexagonal interiorly, the inner ends of the jaws 24 defining a hexagonal socket for receiving the hexagonal head 16 of the cap-screw 15.

An adjusting plug 28 is fitted in the outer end of the body 17, the inner end 29 abutting the adjoining end of the spring collet 23, as shown in Figure 1. The plug 28 is provided with a left-hand threaded portion 30 which is threaded into the internal threaded portion 20 of the body 17. A square wrench-engaging nut portion 31 is carried by the outer end of the plug 28.

45 The operation of the device is as follows:

This device or tool works in close quarters between the radiator outlet 13 and pump outlet 12, after the lower radiator hose is removed. The body 17 is placed within the outlet 12 as shown, 50 and the adjusting plug 28 is rotated in a counter-clockwise direction thereby forcing the spring collet 23 axially inwardly to a point where the inner ends of the spring jaw 24 engage the head 16 of the cap-screw 15. By further rotating the plug 28 in the same direction, the inner ends of

the jaws 24 will be forced radially inwardly upon the head 16 as they ride upon the tapering portion 22 of the body 17, under pressure of the plug 28. The body 17 may be firmly held by one wrench gripping the nut portion 19 while the plug 28 is rotated in a counter-clockwise direction by means of a wrench engaging the nut portion 31.

When the cap-screw 15 has been unthreaded from its position, the spring jaws 24 may be released from the head 16 by threading the plug 28 in a clockwise direction and thereby withdrawing pressure from the spring collet 23, whereupon the spring nature of the jaws 24 will cause the ends of the jaws to spring away from the head 16 and by sliding upon the inclined portion 22 the collet 23 will recede away from the head 16 of the cap-screw 15. The tool may then be removed from the outlet 12.

It should be understood that as the plug 28 is threaded inwardly into the body 17, the plug 28 will frictionally engage and rotate the collet 23, thereby causing the ends of the chisel-like gripping elements to cut away any corrosion which may have formed around the head 16 of the cap-screw 15 and which might prevent the gripping of the head 16 of the cap-screw 15 by the gripping elements. This rotation of the collet 23 with the plug 28 will produce a rotary scraping action upon such corrosion, until the gripping elements reach the hexagonal sides of the head 16; after which, the gripping elements will move axially and radially inwardly through such corrosion, so as to firmly grip the head 16 and thereby facilitate the unthreading of the screw by operating the device as above set forth.

Having described the invention, what is claimed is:

A water pump cap-screw remover comprising a tube-like body to be positioned in a right angularly extending outlet of a water pump, said body having open ends, the body having an inwardly tapering portion at its inner end to define a restricted opening at its inner end for fitting over the head of a water pump anchoring cap-screw, a spring collet slidably fitted in said body for gripping the head of the cap-screw, said tapering portion engaging and forcing the collet into

gripping engagement with the head of the cap-screw, an adjusting plug threaded into said body and frictionally engaging the collet for moving the collet longitudinally of the body and into a cap-screw engaging position, said collet being cylindrical exteriorly, so as to freely rotate with said plug within said body, said collet being hexagonal interiorly and having a plurality of spring jaws having tapering ends contacting said inwardly tapering portion of the body which forces the jaws into gripping engagement with the head of the cap-screw as said plug and collet are moved longitudinally of said body, the ends of said spring jaws also having outwardly beveled inner faces at their extremities to facilitate the placing of the ends of said jaws over the head of a corroded cap-screw and defining a plurality of chisel-like cap-screw gripping elements which will cut away corrosion from around the head of the cap-screw as the plug is rotated until the collet firmly grips the head of the cap-screw, a wrench-engaging portion carried by the outer end of said body, a wrench-engaging portion carried by the outer end of said adjusting plug, and said plug having a left-hand thread formed on a portion of the plug engaging the body so as to feed the plug inwardly of the body when the plug is rotated in a counter-clockwise direction.
